UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

FOLDING AND CUTTING COUPLE FOR FOLDING MACHINES.

Application filed October 3, 1923, Serial No. 666,385. Renewed May 2, 1928.

The principal objects of this invention are to provide each of the folding and cutting cylinders cast in a single piece, doing away with the removable bridges ordinarily employed, and thus reducing the cost of manufacture and especially providing for the mounting of the movable parts without the necessity of machining the supporting and bearing surfaces so that the cylinders and 10 the detachable parts and their connecting means are all formed of castings without finishing. Other objects and advantages of the invention will appear hereinafter.

Reference is to be had to the accompanying drawings, in which

Fig. 1 is an end view of the folding and cutting cylinders of a folding machine showing interior construction in accordance with this invention;

Fig. 2 is a plan of the cutting and folding couple;

Fig. 3 is a sectional view of the same on the line 3—3 of Fig. 2 with the movable and detachable parts omitted, that is, it is a sectional view of the two castings as they are cast and provided with seats for receiving the parts that are to be attached to them;

Fig. 4 is a sectional view of a portion of the folding cylinder showing the folding blade turned to a position to be introduced or removed;

Fig. 5 is an enlarged view of one of the pin holders and its guide; and

Figs. 6 and 7 are sectional views of two forms of cylinders.

The cutting and folding cylinders used in folding machines are made ordinarily of heavy castings which have to be machined a great deal as seats have to be provided for holding brackets and other elements which support the movable folding blades and pins. These cylinders are provided with opposite shafts on which the folding blades are mounted outside which are ordinarily located removable bridges. These bridges have to be finished and the cylinders have to be finished at considerable expense to receive them as well as being finished all over the exterior. This invention relates to a construction in which the expense of providing these features is very largely eliminated.

Referring first to the folding cylinder 10, this is cast in a single piece as shown in Fig. 6 or on a shaft as shown in Fig. 7. In either

case it is cast under size and afterwards an outer layer 9 of soft metal is cast on it with its outer surfaces finished in the act of casting. The journals also have their outer surfaces 8 finished in the same way. The cylinder is provided in the casting operation with openings 11 extending all the way through for the purpose of reducing the weight of the casting. It is also provided with two opposite passages 13 extending outwardly toward the circumference for receiving a pair of opposite blocks 14 for holding the soft pads to receive the edges of the cutting blades on the cutting cylinder.

The folding cylinder is provided with openings 12 located diametrically opposite each other, extending nearly all the way through the cylinder from one end to a solid integral wall at the other, each provided at points at opposite sides of the openings 12 and at its open end with a flat surface having two seats 15 of soft metal alloy capable of setting quickly without material shrinkage and thus capable of being finished in the molds in which it is cast. These seats are cast directly on the rough surfaces of the cylinder, which is cast with depressions for receiving them. They are finished on their outer surfaces in the act of casting. They are held in position in any desired way, but they are permanently mounted on the cylinder. Each pair of these seats receives a bracket 16 which brackets are provided with perforations. In line with these perforations are similar ones in the opposite end wall of the cylinder. These perforations are provided with soft metal bearings 47 and 48 permanently cast in position and finished interiorly in the act of casting. They carry the impaling pin shaft 17. This shaft has a crank 18 provided with a cam roller 19 adapted to be oscillated by a cam of the usual kind, not shown. Each shaft 17 also has arms 20 each pivotally connected with the end of a pin holder 21, the latter being screwed into an oscillatingly mounted stud 22 in the arm 20. This pin holder is provided with an impaling pin 23 for the usual purpose.

The impaling pin is guided in a cylindrical stud or guide 24 which is fixed in position in a body of soft metal alloy 25 such as that described above, and cast in a cylindrical opening in the casting 10. This soft metal seat is provided with projecting surfaces on

two sides at right angles to each other for the purpose of supporting the blocks 14. This soft metal seat 25 is cast permanently in position in the cylinder and provided with finished cast surfaces for supporting the block and the guide 24. The pin holder 21 passes through this guide and out to the circumference of the cylinder where it operates in the usual manner.

10 Also located at diametrically opposite sides of the cylinder are two longitudinal openings 26. These openings do not extend all the way through the cylinder. There is a wall at one end so that that end of the cylinder is not perforated at these points, but at the other end the opening extends all the way through.

These openings 26 are interrupted at intervals by a series of bridges 27 extending 20 across them and formed integrally in the act of casting the cylinder 10. These bridges are continuous with the exterior surface of the cylinder and perform the same function as the ordinary removable bridges, but obviously do not require any machining inside. These openings 26 are cylindrical in cross section and have soft metal seats 28 cast in position at their open ends in the manner above described to permit of the mounting 25 of brackets 29 therein. These brackets 29 have soft metal bearings 31 cast in finished form for a folding blade shaft 30. The other end of each shaft is carried in a similar bearing 31 in the opposite end wall. These two 30 bearings 31 are carefully cast in alignment with their inner surfaces finished in the casting operation. Two of these shafts extend along the roll in the usual way through these openings and are provided with the usual 35 folding blades 32 acting to tuck the folded product between the folding rolls. These blades project through the spaces between the bridges as usual. The shafts 30 are provided with gears 33 to be operated by the usual gears and timed to rotate as usual. The openings 26 between the bridges 27 are curved substantially on a semi-circle to give room for the blades 32 to swing in them. Under the bridges the openings 46 are of triangular shape to allow the folding blades and 40 shafts to be inserted. The soft metal surfaces 9 and 25 can be integral with each other if desired.

In the assembly of these parts the brackets 55 29 are placed on the folding shaft 30 and both inserted endwise from the open end of the cylinder with the folding blade located in the position shown in Fig. 4 so that it can be inserted in the triangular openings. Likewise if there is any necessity of removing them they can be taken out in the same way.

The cutting cylinder 35 is constructed on the same principle as the folding cylinder. It has the usual knife 36 and impaling pins 37 operating in guides 38 and moved by arms

39 on a longitudinal shaft 40. This cylinder is cast with an opening 41 all the way across it for this shaft 40 and is provided with flat surfaces 42 having soft metal seats 43 cast thereon for brackets 44 for mounting this shaft. The guides 38 are mounted in soft metal seats 45 for the same purpose as in the folding cylinder. An external layer 49 of soft metal like the layer 9 is also shown for the same purpose. The cutting cylinder being more simple than the folding cylinder no further description of the details need be given.

In this way it will be seen that these cylinders can each be formed from a single piece of cast iron with a minimum of weight and in such a way that no machining of the cylinder is necessary. The soft metal seats and surfaces can be put on by the application of suitable molds. The work is simple and requires very little skilled labor with the exception of making the molds for the soft metal. The parts are accurately located in position, the soft metal seats are permanent, the detachable parts can be inserted in the manner described in a very convenient way, and the whole device can be set up and gotten into working shape without setting the cylinder up in a lathe or other machine tooling.

Although I have illustrated and described only a single form of the invention as applied to the folding cylinder and a single form as applied to the cutting cylinder I am aware of the fact that other modifications can be made therein by any person skilled in the art without departing from the scope of the invention as expressed in the claims.

Therefore I do not wish to be limited to all the details of construction herein shown and described, but what I do claim is:

1. As an article of manufacture, a cylinder forming one of the cutting and folding couple of a folding machine, consisting of metal cast with a longitudinal opening, said opening being provided with a plurality of bearings of relatively soft metal cast in finished condition for rotatably supporting a shaft, whereby the machining of the surfaces of the cylinder is avoided.

2. A cylinder forming one of the cutting and folding couple of a folding machine, consisting of a single body of cast hard metal provided in the act of casting with a longitudinal opening through one end extending toward the other, said opening having at the open end seats of relatively soft metal cast with finished seating surfaces, and a bracket secured on said surfaces and having a soft metal bearing finished in the act of casting to fit its shaft, without necessitating the machining of the surfaces of the cylinder.

3. A folding machine cylinder cast with a solid end wall and an opening extending therefrom to the opposite end of the cylinder,

and with flat surfaces at the open end, soft metal seats cast in finished form on said surfaces, a bracket fastened to the cylinder on said seats as cast, said bracket and the end 5 wall having opposite perforations, and circular bearings for a shaft cast in finished form in alignment in said perforations.

4. As an article of manufacture, a cylinder for the purpose described formed of a single 10 body of cast hard metal and having a pair of opposite openings extending therealong and provided with a series of integral bridges across it having passages of triangular shape in cross-section for receiving therein folding 15 blade shafts, one of the angles of the triangle being of such length as to receive therein the folding blade on its shaft to permit of the insertion of the blade and shaft from the end.

20 5. As an article of manufacture, a cylinder for the purpose described formed of cast metal and provided with a pair of opposite openings therethrough extending from one end nearly to the other, the cylinder having 25 flat surfaces adjacent to said opening, and soft metal seats permanently cast on said flat surfaces and having surfaces finished in the casting operation for the reception without machine finishing of brackets for 30 supporting a longitudinal shaft.

6. As an article of manufacture, a cylinder constituting a member of a cutting and folding couple having an integral portion and means produced in finished state by casting 35 for supporting a pair of parallel shafts in definite position with relation to said integral portion therein, whereby the shaft can be mounted in position within the cylinder back of said integral portion thereof without 40 machining the cylinder.

7. As an article of manufacture, a cylinder for the purpose described formed of a single 45 body of cast metal and provided with a pair of opposite openings therethrough extending from one end nearly to the other, the cylinder having flat surfaces adjacent to said opening and soft metal seats permanently cast on said flat surfaces and having formed in the casting operation seating surfaces 50 ready for the reception without machine finishing of brackets for supporting a longitudinal shaft, the cylinder being provided with integral cast bridges over said openings at intervals and having an exterior surface constituting part of the surface of said cylinder and continuous therewith.

8. The combination with a cylinder of the 55 class described having a longitudinal passage, of a bracket located at the end of said 60 passage, soft metal seats for said bracket cast in position and in finished form therein, a shaft carried by said brackets within the cylinder, arms on said shaft, and impaling pins pivotally connected with said arms.

65 9. The combination with a cylinder of the

class described having a longitudinal passage, of a bracket located in said passage, soft metal seats for said bracket cast in position and in finished form therein, a shaft carried by said bracket within the cylinder, arms on 70 said shaft, impaling pins pivotally connected with said arms, a guide for each pin having a passage therethrough for the pin, and a soft metal seat cast in said cylinder around said guide to form a bearing for it and hold 75 it in position accurately without finishing the adjacent surfaces of the cylinder.

10. The combination with a cylinder of the class described having a longitudinal passage parallel with the axis, of a bracket extending into said passage, said cylinder having cast soft metal seats for said bracket to avoid the finishing of the surfaces of the cylinder, a shaft carried by said bracket within the cylinder, arms on said shaft, impaling 80 pins pivotally connected with said arms, a guide for each pin having a passage therethrough for the pin, and a soft metal seat cast in said cylinder around said guide to hold it in position accurately, said soft metal 85 seat extending therefrom and providing a seat for a block to be located on the surface of the cylinder.

11. The combination with a cylinder for the purpose described having an opening cast 90 therein, of a cylindrical guide located in said opening centrally, a seat of soft metal cast in said opening around the guide to constitute an accurate bearing surface for the guide, said guide having a passage therethrough, 95 and an impaling pin movably mounted in said passage and guided thereby.

12. A folding cylinder having bearings for a rotatable folding blade shaft cast therein with its bearing surfaces in finished form. 100

13. A folding cylinder having bearings for an oscillatable folding blade shaft cast therein in finished form and integral seats for an impaling pin block also cast in the cylinder with its seating surfaces in final finished 110 form.

14. A cylinder constituting a member of a folding and cutting couple having bearings for an impaling pin shaft cast therein with its bearing surfaces in finished form. 115

15. A cylinder constituting a member of a folding and cutting couple having bearings for an impaling pin shaft cast therein in finished form, and seats for impaling pin 120 guides cast therein with their bearing surfaces finished in the act of casting.

16. A cylinder constituting a member of a folding couple comprising a body of hard cast metal provided with a surface layer of soft metal cast thereon with its external surface finished in the act of casting so that it requires no machining on its cylindrical surface. 125

17. As an article of manufacture, a folding cylinder of hard cast metal having its cylin- 130

drical exterior surface and the surfaces of its journals formed of soft metal finished in the act of casting.

18. As an article of manufacture, a cylinder forming one member of the cutting couple of a folding machine consisting of hard metal cast with a longitudinal opening, said opening being provided with a seat of a softer metal cast in place in the finished state for supporting a male or female cutting knife.

19. As an article of manufacture, a cylinder forming one member of the cutting couple of a folding machine, consisting of hard metal cast with a longitudinal opening, said opening being provided with a seat or seats

of softer metal cast in place in the finished state for supporting means for folding the sheet.

20. As an article of manufacture, a cylinder forming one member of the cutting couple of a folding machine, consisting of hard metal cast with a longitudinal opening, said opening being provided with a seat or seats of softer metal cast in place in the finished state for supporting means for impaling the sheet.

In testimony whereof I have hereunto affixed my signature.

HENRY A. WISE WOOD.
